(57) **ABSTRACT**

A new distinct variety of grapevine named 'ARD51' abundantly forms attractive crunchy and juicy seedless berries with a red skin coloration, lax density and large clusters which display a natural sweet flavor, the fruit commonly is ready for harvesting during July in San Joaquin Valley of Central California, U.S.A., and displays good eating qualities as a table grape, the fruit firmness renders the fruit well amenable for handling, shipping, and storage.

1 Drawing Sheet

1

Classification: The present invention relates to a new *Vitis vinifera* Grapevine.

Variety denomination: The new Grapevine has a varietal denomination 'ARD51'.

BACKGROUND OF THE INVENTION

A breeding program was initiated during the late 90's near Bakersfield in San Joaquin Valley of Central California. In 2018, during this breeding program, a new variety of *Vitis vinifera* was created by deliberate cross breeding of two parent plants by emasculation of the pollen bearing organ of the female and introducing pollen from another male origin. The female parent of the new variety was 35-33+6, which is a white, crunchy and slightly juicy variety (non-patented in the United States). The male parent (i.e. the pollen parent) of the new variety was 30A-11+3, a red, crispy and juicy variety (non-patented in the United States).

TABLE 1

'ARD51' compared with parents & closely related variety:				
	'ARD51'	35-33+6	30A-11+3	Flame
Brix	21	17	18	16-20
Texture	Crunchy & juicy	Crunchy	Crispy	Crispy
Berry shape	Broad ellipsoid	Obtuse ovoid	Broad ellipsoid	Globose

The parentage of the new variety can be summarized as follows: 35-33+6 X 30A-11+3

An artificial pollination was created, and the result was an embryo which possessed unique genetic qualities. The rudiments resulting from the above pollination were embryo rescued.

2

In 2019 the plant was transplanted to Bakersfield in San Joaquin Valley of Central California.

It was found that the new grapevine of the present invention possesses the following combination of characteristics:

- (a) Forms attractive crunchy and juicy seedless berries with a red skin coloration; in lax density and large clusters which display a natural sweet flavor,
- (b) Commonly bears fruit during the month of July in the San Joaquin Valley of Central California, U.S.A., and
- (c) Bears fruit that is firm and is well amenable for storage, handling, and shipping.
- (d) Produces 44 bunches per vine, and an average of about 2 bunches per shoot, at a total of 51 lbs. fruit per vine.

The new variety during observation to date has displayed no visible disease, and has displayed an ability to well resist cold, drought, heat; but sensitive to direct exposure to sun and wind. The fruit of the new variety has been found to display excellent handling and shipping qualities combined with desirable dessert eating qualities.

The new variety of the present invention has been found to undergo asexual propagation beginning in 2020 near Bakersfield in the San Joaquin Valley of Central California, U.S.A. by bud grafting on mature Thompson Seedless rootstock (non-patented in the United States). Such asexual propagation has been conducted thereafter in successive years to date and has shown that the characteristics of the new variety are strictly transmissible from one generation to another. Accordingly, the new variety undergoes asexual propagation in a true to type manner.

SUMMARY OF THE INVENTION

The new variety 'ARD51' is a red, naturally sweet seedless grape variety with high production, e.g., about 44 bunches per vine, and an average of about 2 bunches per shoot.

Asexual reproduction by micro propagation of the new variety as performed near Bakersfield, California, U.S.A., shows that the forgoing and other distinguishing characteristics come true to form and are established and transmitted through succeeding propagations.

BRIEF DESCRIPTION OF THE DRAWING

The accompanying photographic illustration shows typical five-year-old specimens of the new variety, vegetatively propagated, in color as nearly true as it is reasonably possible to make in a color illustration of this character. Colors in the photograph may differ from the color values cited in the detailed botanical description below, which accurately describes the colors of the new Grapevine.

The drawing shows leaves, stems, tendrils and grapes of 'ARD51'.

DETAILED BOTANICAL DESCRIPTION

The chart used in the identification of colors is The R.H.S. Colour Chart of The ROYAL HORTICULTURAL SOCIETY (3rd Edition). The description is based on the observation of plants growing on 'Thompson Seedless' rootstock outdoors near San Joaquin Valley of Central California, U.S.A.

TABLE 2

VINE CHARACTERISTICS:

vigor	Vigorous upright shoots
productive capacity	Bearing at a natural, average capacity. Spur pruning.
trunk	Strong and developed. Diameter is 2.4 inches at 4.5 inches above ground. Rough with a fibrous, shaggy exterior. Light maple brown coloring greyed orange 177 B

Date of bud burst in Bakersfield California: March 4th.

TABLE 3

YOUNG SHOOT CHARACTERISTICS:

Openness of tip	Wide open
Density of prostrate hairs on tip	Dense
Anthocyanin coloration of prostrate hairs on tip	None
Density of erect hairs on tip	Medium

TABLE 4

YOUNG LEAF CHARACTERISTICS:

Color of upper side of blade	Yellow green 146 B
Color of lower side of blade	Yellow green 146 C
Density of erect hairs between main veins on upper side of blade	Dense
Density of erect hairs between main veins on lower side of blade	Dense
Density of prostrate hairs on main veins on upper side of blade	Dense
Density of prostrate hairs on main veins on lower side of blade	Dense

TABLE 5

SHOOT CHARACTERISTICS:	
5	Attitude (before tying) Semi-erect
	Color of dorsal side of internodes Yellow Green 144 A
	Color of ventral side of internodes Yellow Green 144 A
	Color of dorsal side of nodes Yellow Green 144 B
	Color of ventral side of nodes Yellow Green 144 B
	Density of erect hairs on internodes Absent or very sparse
	Density of prostrate hairs on internodes Absent or very sparse
10	Length of tendrils 7.5 inches
	Diameter of tendrils 0.09 inches
	Color of tendrils Yellow green 144 A
	Number of tendrils at bloom 4
	Positioning of first flowering and fruiting node The first bunch is in the 3 rd node
15	Inflorescence number per flowering shoot 2

TABLE 6

FLOWER CHARACTERISTICS:	
20	Reproductive organs Fully developed stamens and fully developed gynoecium
	Flower length 0.3 inches
	Flower diameter 0.2 inches
	Pistil length 0.14 inches
	Pistil color Yellow green 144 A
25	Pollen Amount Rich
	Pollen color Yellow 10 A
	Stamen color Yellow green 145 C
	Stamen length 0.19 inches
30	Number of stamen 6

35 ..
First bloom in Bakersfield, California: April 23rd.
Date of full bloom in Bakersfield, California: May 1st.

TABLE 7

MATURE LEAF CHARACTERISTICS:	
40	Size of blade 6.5 inches x 6.5 inches
	Shape of blade Circular
	Base descriptors Pentagonal
	Leaf margin Serrate
	Leaf apex Acute
	Blistering of upper side of blade Absent or very sparse
	Depth of upper lateral sinuses Shallow
	Number of lobes Five
	(Only varieties with lobed leaves) Open
	Arrangement of lobes of upper lateral sinuses
45	Arrangement of lobes of petiole sinus Half open
	Length of teeth 0.27 inches
	Ratio length/width of teeth Small
	Shape of teeth Both sides concave
	Density of prostrate hairs between main veins on lower side of blade Absent or very sparse
	Density of erect hairs on main veins on lower side of blade
50	Absent or very sparse
	Density of erect hairs between the main veins on upper side of blade
	Absent or very sparse
	Density of prostrate hairs on main veins on upper side of blade
	Absent or very sparse
55	Length of petiole compared to length of middle vein Moderately shorter
	Top side color Green 137 A
	Bottom side color Green 138 B
	Texture of upper side of blade Smooth
	Texture of lower side of blade Smooth
60	Vein color on upper blade Yellow Green 145 A

TABLE 7-continued

MATURE LEAF CHARACTERISTICS:	
Anthocyanin coloration of main veins on upper side of blade	Red 53 A
Vein color on lower blade	Yellow green 145 C
Venation pattern for upper blade	Netlike venation
Venation pattern for lower blade	Netlike venation
Petiole length	2.5 inches
Petiole diameter	0.1 inches
Petiole color	Red 53 A
Petiole texture	Smooth

Date of beginning of berry ripening in Bakersfield California: June 2nd.

TABLE 8

BUNCH CHARACTERISTICS:	
Size (peduncle excluded)	Large
Density of berries on bunch	Lax
Bunch length	9.5 inches
Bunch diameter	4.8 inches
Length of peduncle of primary bunch	0.84 inches
Diameter of peduncle of primary bunch	0.11 inches
Peduncle of primary bunch color	Yellow green 144 B
Peduncle texture	Smooth
Bunches per vine	44
Average bunch weight	1.16 lbs

TABLE 9

BERRY CHARACTERISTICS:	
Size	Large
Length	1.4 inches
Weight	0.35 oz
Diameter	0.09 inches
Shape	Broad ellipsoid
Color of skin (without bloom)	Red 45 D
Flesh color	Yellow green 145 D
Brix	21
Titratable acidity percentage	0.33%
Juice	4.09 pH
Ease of detachment from pedicel	Moderately easy
Thickness of skin	Thin
Anthocyanin coloration of flesh	None
Firmness of flesh	Moderately firm
Particular flavor	Naturally sweet
Formation of seeds	Rudimentary
Berries per bunch	53
Juiciness of the berry flesh	Juicy

TABLE 10

PEDICEL CHARACTERISTICS:	
Length	0.51 inches
Diameter	0.13 inches
Color	Green 143 C
Pedicel texture	Rough

TABLE 11

WOODY SHOOT CHARACTERISTICS:	
5	Woody shoot texture
	Woody shoot color
	Woody shoot length
	Diameter
	Internode length
	Rough
	Greyed orange 165 B
	274 inches
	0.4 inches
	2.8 inches

10 Market use of observed plants: Fresh market.
 Age and growing conditions: Six years growing under Y system in South Joaquin Valley (hot, dry summers).
 Shipping characteristics: (E.g. number of days fruit has been stored under specific conditions): Fruit was in cold storage. Stored in poly bags inside polystyrene boxes with sulfur pads. After 30 Days rachises were 90% green; 5% berry shattering; no berry wrinkling or cracks were apparent.
 15 DNA profile: To further characterize the new variety DNA was extracted from plant samples and a DNA profile was obtained at California Seed & Plant Lab, California USA using base pairs for 10 standard microsatellite DNA markers. The data is presented hereafter.

TABLE 12

DNA profile for ARD51		
	Microsatellite DNA Marker	Allele Sizes in Base Pairs
30	M 1	234
	M 2	247
	M 3	179
	M 4	210
	M 5	271
	M 6	131
	M 7	189
	M 8	255
	M 9	212
	M 10	247

35 The 'ARD51' variety has not been observed under all possible environmental conditions to date. Accordingly, it is possible that the phenotypic expression may vary somewhat with changes in light intensity and duration, cultural practices, and other environmental conditions.

40 Additional information relating to plant and fruit disease and pest resistance or susceptibility has not been observed to date. Specification of the plant hardiness zone and the heat/cold resistance has not been observed to date.

45 What is claimed is:

50 1. A new and distinct grapevine plant, botanically known as *Vitis vinifera*, identified as 'ARD51', substantially as shown and described herein.
